GILBERT W. GOODRIDGE, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

ELECTRIC SWITCH.

1,201,170.

Specification of Letters Patent. Patented Oct. 10, 1916.

Application filed April 25, 1913. Serial No. 763,604.

To all whom it may concern:

Be it known that I, GILBERT W. GOODRIDGE, a citizen of the United States of America, and residing at Bridgeport, in the county of Fairfield and State of Connecticut, have invented a certain new and useful Improvement in Electric Switches, of which the following is a specification.

My invention relates to electric switches and particularly to the type of switch adapted to be mounted in an electric lamp socket, the object of my invention being to provide a simple and efficient mechanism of improved type.

In the accompanying drawings, Figure 1 is a vertical section through a lamp socket in which my invention is embodied in one form; Fig. 2 is a plan of this switch mechanism in position on one of the buttons forming the socket body; Fig. 3 is a vertical section through the switch mechanism on the line 3—3, Fig. 2; and Fig. 4 is a perspective of certain of the switch parts separated. Fig. 5 is an end elevation of the switch spindle showing the position of the operating cams thereon.

The present switch is of the type in which an oscillating switch piece is rocked on its pivot by a switch spring, one end of which is shifted to one side or the other of the axis of oscillation of the switch piece, by a manually controlled operating mechanism. The socket in which the switch is here embodied comprises the usual casing cap 5 and shell 6, with insulating lining 7. The socket body of insulating material is formed from two buttons A and B united by screw bolts 8 and recessed on their meeting faces to form a switch chamber 9. Lateral recesses 10 and 11 accommodate the wire terminals 12 and 13, one of the latter being in constant connection with the shell terminal 14 of the socket, and the other in constant connection with the switch terminal 15. The other switch terminal 16 is preferably formed in one with the center contact 17 of the socket and is secured with the latter by the rivet 18 in known manner.

Within the switch chamber 9 is mounted the switch frame 19 held in position by the screw 20. While the frame may be of any suitable form, that here shown is shaped from sheet metal bent to form end uprights 21 and side uprights 22. Outwardly projecting lugs 23 on the latter serve as pivots

for the yoke-shaped switch piece 24 which oscillates from the position shown in Fig. 3 where the switch is "off", to the position shown in Fig. 1, where the switch is "on" and the closed end of the yoke lies between 60 and electrically connects the two switch terminals 15 and 16.

The oscillation of the switch is effected by the switch spring 25 mounted on the plunger 26 and bearing at one end against 65 the closed end of the yoke (through which the end of the plunger passes) and at its other end against the head 27 of the plunger. The latter is subject to the vertical movement of the rocker 28, with which it is engaged in any suitable manner, for example, by means of a sort of bayonet slot joint between the slot and aperture 29 in the head 27 and the cross bar 30 formed in the end of the rocker. Obviously as the head of the 70 plunger is shifted past the axis of oscillation of the switch piece 24 in one direction or the other, the spring 25 is not only further tensioned, but its effort is directed to throw the switch yoke into either the "off" 80 or "on" position, as may be, depending upon the side of the axis of oscillation to which the head 27 of the plunger has been shifted.

The movement of the plunger, as above stated, is controlled by the rocker 28, the 85 axis 31 of which is pivoted in the side uprights of the frame. The rocker in turn is subject to the rotation of the switch key 32 on the spindle of which are mounted, at right angles to each other, the two cams 33 90 and 34 spaced apart and bearing, in assembled condition, against the lower face of the rocker 28 on opposite sides of its axis of oscillation. In the position shown in Fig. 3, the head 27 of the plunger has been depressed through the action of the cam 33 on the rocker 28. On a quarter turn of the switch key the cam 33 becomes temporarily inoperative, while the cam 34 turning into vertical position tilts the rocker 28 in the opposite direction, thus lifting the head 27 of the plunger. A further quarter turn of the switch key restores the switch to its first position through the action of cam 33, 95 and so on. Inasmuch as the cams are double acting, a quarter turn of the switch key in either direction, brings one or the other of the cams 33, 34 into effective operation to oscillate the switch piece through the tilting of the rocker 28.

105

100

110

The construction shown is but an illustrative embodiment of my invention, various modifications of which will readily suggest themselves.

5. I claim as my invention:—

1. In an electric switch, an oscillating switch piece, a spring one end of which is operatively connected to said switch piece to effect its oscillation, an oscillating rocker 10 to one end of which the other end of said switch spring is operatively connected, a switch spindle arranged at an angle to the axis of oscillation of said switch piece, and means thereon for tilting said rocker to shift 15 said end thereof past the axis of oscillation of the switch piece.

2. In an electric switch, an oscillating switch piece, a spring one end of which is operatively connected to said switch piece 20 to effect its oscillation, an oscillating rocker having an axis substantially parallel to that of the switch piece, an operative connection between one end of said rocker and the other end of said switch spring, and means for 25 oscillating the rocker to shift said end thereof past the axis of oscillation of the switch piece, said means comprising a switch spindle having an axis arranged at an angle to the axis of the switch piece, and means on 30 said spindle operatively engaging said rocker to actuate the latter on the rotation of the spindle.

3. In an electric switch, an oscillating switch piece, a spring one end of which is 35 operatively connected to said switch piece to effect its oscillation, an oscillating rocker having an axis substantially parallel to that of the switch piece, an operative connection between one end of said rocker and the 40 other end of said switch spring, in combination with a switch spindle and means thereon engaging the rocker on opposite sides of its axis to shift said end past the axis of oscillation of the switch piece.

4. In an electric switch, an oscillating switch piece, a spring one end of which is operatively connected to said switch piece to effect its oscillation, an oscillating rocker having an axis substantially parallel to that 50 of the switch piece, an operative connection between one end of said rocker and the other end of said switch spring, in combination with a rotary switch spindle, and cam means thereon engaging said rocker on opposite 55 sides of its axis to tilt the rocker to shift said end past the axis of oscillation of the switch piece.

5. In an electric switch, an oscillating switch piece, a spring one end of which is 60 operatively connected to said switch piece to effect its oscillation, an oscillating rocker having an axis substantially parallel to that of the switch piece, an operative connection between one end of said rocker and the other 65 end of said switch spring, a rotary switch

spindle, and cams set at an angle to each other on said spindle and on opposite sides of the axis of said rocker and engaging the latter on the rotation of the spindle to shift the spring-engaging end of said rocker past 70 the axis of oscillation of the switch.

6. In an electric switch, an oscillating switch piece, a spring one end of which is operatively connected to said switch piece to effect its oscillation, an oscillating rocker 75 having an axis substantially parallel to that of the switch piece, an operative connection between one end of said rocker and the other end of said switch spring, a rotary switch spindle arranged at an angle to the axis of 80 oscillation of the switch piece, and cams set at an angle to each other on said spindle and on opposite sides of the axis of said rocker and engaging the latter on the rotation of the spindle to shift the spring-engaging end of said rocker past the axis of 85 oscillation of the switch.

7. In an electric switch, an oscillating switch piece, a spring one end of which is operatively connected to said switch piece 90 to effect its oscillation, an oscillating rocker having an axis substantially parallel to that of the switch piece, an operative connection between one end of said rocker and the other end of said switch spring, a switch spindle 95 freely rotatable in opposite directions, and cams set at an angle to each other on said spindle and on opposite sides of the axis of said rocker and engaging the latter on the rotation of the spindle in either direction 100 to shift the spring-engaging end of said rocker past the axis of oscillation of the switch.

8. In an electric switch, an oscillating switch piece, a spring one end of which is 105 operatively connected to said switch piece to effect its oscillation, an oscillating rocker having an axis substantially parallel to that of the switch piece, an operative connection between one end of said rocker and the other end of said switch spring, a rotary switch spindle, and cams set at right angles to each other on said spindle and on opposite sides of the axis of said rocker and engaging the latter on the rotation of the spindle through 110 a quarter turn to shift the spring-engaging end of said rocker past the axis of oscillation of the switch.

9. In an electric switch, an oscillating switch piece, a spring one end of which is 115 operatively connected to said switch piece to effect its oscillation, an oscillating rocker having an axis substantially parallel to that of the switch piece, an operative connection between one end of said rocker and the other end of said switch spring, a switch spindle freely rotatable in opposite directions, and cams arranged thereon at an angle of 90° to each other on opposite sides of the axis of said rocker and engaging the latter 120

125

on the rotation of the spindle through a quarter turn thereof in either direction to shift the spring-engaging-end of said rocker past the axis of oscillation of the switch.

5 10. In an electric switch, an oscillating U-shaped switch piece, a guide passing freely through the end of said switch piece, a switch spring arranged on said guide and bearing against the free end of said switch piece, an oscillating rocker having an axis substantially parallel to that of the switch piece and jointed at one side of its axis to said spring guide, in combination with means engaging said rocker to tilt the latter 15 to shift the end of said guide engaged thereby past the axis of oscillation of the switch piece.

11. In an electric switch, the combination of a supporting frame, a switch member pivoted on said frame, a plate connected to the switch member, a pin mounted on the frame and constituting a fulcrum for said plate, a spindle, and cams on the spindle and capable of engaging the plate on opposite 25 sides of its fulcrum to rock the plate on said pin as a fulcrum.

12. In an electric switch, the combination of a supporting frame, a switch member pivoted on said frame, and means rocking said member on its pivot comprising a spindle mounted on the frame, a pair of cams fixed on the spindle, a plate and a pin extending across said frame between the cams and constituting a pivot for said plate, the under 30 side of said plate being engageable by said cams to rock the plate on its pivot.

13. In an electric switch, the combination

of a supporting frame, a switch member pivoted on said frame, and means rocking said member on its pivot comprising a spindle mounted on the frame, a pair of cams fixed on the spindle, a plate and a pin extending across said frame between the cams and constituting a pivot for said plate, the under side of said plate being engageable 40 by said cams to rock the plate on its pivot, a pin connected to said plate and said switch member, a spring surrounding said pin and pressing against said switch member, the connections between the pin and plate being 45 so located that the oscillation of the plate on its pivot will throw the end thereof connected to said pin across the pivotal connection between said switch member and frame. 50

14. In an electric switch, the combination of a supporting frame, a switch member pivoted on said supporting frame, a spindle extending transversely of the pivotal support on said switch member, a plate connected to said switch member, a pivot pin for said plate extending substantially parallel to the pivotal support of said switch member and cam means on the spindle capable of engaging the under side of said 60 plate to rock it on said pin. 65

In testimony whereof I have signed my name to this specification, in the presence of two subscribing witnesses.

GILBERT W. GOODRIDGE.
